F. S. GREGUR.
SIGNAL STAFF FOR RAILROADS.
APPLICATION FILED MAY 1, 1915.

1,207,898.

Patented Dec. 12, 1916.

UNITED STATES PATENT OFFICE.

FRANK S. GREGUR, OF WEST BROWNSVILLE, PENNSYLVANIA.

SIGNAL-STAFF FOR RAILROADS.

1,267,898.

Specification of Letters Patent. Patented Dec. 12, 1916.

Application filed May 1, 1915. Serial No. 25,257.

To all whom it may concern:

Be it known that I, FRANK S. GREGUR, a citizen of the United States, residing at West Brownsville, in the county of Washington and State of Pennsylvania, have invented certain new and useful Improvements in Signal-Staffs for Railroads, of which the following is a specification.

This invention relates to signal staffs, adapted for temporary use on railways to protect workmen, for indicating a closed track and for giving various warnings to approaching trains.

An object of the invention is to provide a track engageable member, to permit use of the staff at any point on the railway, and being supported in a desired upright position by the rails, to be discernible at an appreciable distance.

Another object is to provide a staff which will be positively engaged with the rail by merely dropping the staff into engagement with the rail, after the rail-engaging portions have been properly positioned in proximity to the rail; the staff being automatically disengaged from the rail by the exertion of pressure upwardly on the staff.

Other objects as well as the nature, characteristic features and scope of my invention will be more readily understood from the following description taken in connection with the accompanying drawings and pointed out in the claims forming a part of this specification.

Referring to the drawings: Figure 1 is a perspective view of my improved indicating staff illustrating the application of the invention, Fig. 2 is a detail enlarged fragmentary sectional view of the same, and Fig. 3 is a sectional view taken on the line 4—4 of Fig. 2 and looking in the direction of the arrows.

In the drawings in order to illustrate the application of my invention, I have shown a rail 1 which is of the usual configuration.

My improved indicating staff is designed in the drawings at 2 and comprises a tubular body portion 3, which is provided with diametrically opposite longitudinally extending slots 4, approximately midway its ends. The upper outer periphery of the body 3 is provided with external screw-threads adapted for threaded engagement with a nipple 5, the latter having its outer end constricted as indicated at 6 and provided with internal threads for engagement

with corresponding threads upon the lower end of a signal supporting standard 7.

Movably mounted in the body 3 are floating shanks 14, the latter having enlarged lower ends, the terminals of which are formed to provide jaws 15 of a configuration identical with the contour of the rail 1 and adapted to embrace the latter, as illustrated to advantage in Figs. 1 and 2. The jaws 15 are engaged with the opposite sides of the head of the rail, the opposite sides of the splice bar and have feet 16 thereon which engage the base flange of the rail to provide a substantial base, thereby preventing casual displacement of the jaws laterally of the rails. The upper ends of the shanks 14 are pivoted, as indicated at 17 and crossed. The free terminals of the crossed ends are arcuate as shown at 18 and extended through the diametrically opposite opening 4 to provide operating portions in order to automatically expand the jaws 15, for disengaging the same from the rail 1, when pressure is exerted upon the body 3 upwardly in the direction of the standard 7.

In operation, therefore when it is desired to engage the staff with the rail 1, the jaws 15 are permitted to depend beyond the lower end of the body 3, in which position, the arcuate ends 18 of the shanks 14 are in engagement with the body 3 at the lower terminals of the slots 4. Either one of the jaws 15 is then snugly engaged on the rail, which may be done by placing the jaw which is to embrace the rail in parallelism with the latter, and then exerting pressure on the staff at any point. The other jaw will then be automatically engaged with the rail by merely releasing pressure from the staff, permitting the body 3 to drop, the lower end of which will engage the shank 14 adjacent the jaws 15, and cause the latter to be snugly engaged with the rail. When it is desired to disengage the staff from the rail, pressure is exerted on the staff at any point, which operation will cause the movement of the body 3, so that by continued exertion of pressure, the portion of the body at the lower terminal of the slot 4 will contact with the arcuate ends 18 of the shank 14, so as to automatically expand the jaws 15, thereby disengaging the same from the rail and permitting removal of the staff.

It will be understood that the above description and accompanying drawings com-

prehend only the general and preferred embodiment of my invention and that various minor changes in details of construction, proportion and arrangement of parts may 5 be made within the scope of the appended claims without sacrificing any of the advantages of my invention.

Having thus fully described my invention, what I claim as new and desire to secure by Letters Patent is:

- 10 1. A signal staff for railroads including jaws to embrace the rails having shanks extending therefrom to provide operating portions, and a signal bearing standard movably associated with said jaws to automatically clamp the latter on the rail, when the standard is dropped, said operating portions being actuated by movement of the standard in the opposite direction, to disengage 15 the jaws from the rail.
- 20 2. A signal staff for railroads including

jaws to embrace a rail, means in connection with said jaws to gravitate thereon for automatically clamping said jaws in engagement with the rail when said means is released, and a signal standard carried by said means for elevating the latter to disengage 25 said jaws.

3. A signal staff for railroads and including automatically expansible and contractible jaws, and a body slidably associated with said jaws to contract the same into snug engagement with the rail when said body is moved in one direction, the jaws being automatically expanded when the 30 body is moved in the opposite direction.

In testimony whereof I affix my signature in presence of two witnesses.

FRANK S. GREGUR.
